UNITED STATES PATENT OFFICE.

ADAM HEIM, OF CONNERSVILLE, INDIANA.

BALING-PRESS.

1,031,444.

Specification of Letters Patent.

Patented July 2, 1912.

Application filed April 29, 1911. Serial No. 624,046.

To all whom it may concern:

Be it known that I, ADAM HEIM, a citizen of the United States, residing at Connerville, Indiana, have invented a new and useful Improvement in Baling-Presses, of which the following is a specification.

My invention relates to baling presses adapted for use in baling hay, straw or other suitable material and the objects of my improvements are to provide automatic mechanism for tying the bales; to provide the plunger head with twister gears; to provide cutter arms for manipulating the tie wire; to provide novel connections with the plunger head for actuating said arms at predetermined intervals; to provide automatic means for regulating the size of the bales and to provide simple and durable construction and assemblage of the various parts for securing facility of operation and efficiency of action. These objects may be attained in the following described manner, as illustrated in the accompanying drawings, in which:

Figure 1 is a plan of a baling press embodying my improvements; Fig. 2 a side elevation; Fig. 3, a detail of portions of Fig. 2 showing the movement of the latch by the forward stroke of the plunger; Fig. 4 a cross section of the plunger on the broken line 4—4 of Fig. 5; Fig. 5 a longitudinal section with parts broken away showing the position of the twisters in relation to the transverse openings in the plunger; Fig. 6 a horizontal section on the broken line 6—6 of Fig. 5; Fig. 7 a horizontal section through one of the twisters showing the swinging arms crossed within the plunger; Fig. 8 a longitudinal section on the line 8—8 of Fig. 4; Fig. 9 a front elevation of the wire cutter and wire clamp on the extremity of one of the swinging arms; Figs. 10 and 11 side and front elevations respectively of the wire holding finger on the extremity of the opposite swinging arm; Figs. 12 and 13 a side elevation and an inverted plan respectively of the plunger connections for actuating the rack plate and the swinging arms; Fig. 14 shows parts of Fig. 13 in different operative position; Fig. 15 a detail in vertical section on the broken line 15—15 of Fig. 13 and Fig. 16 an end elevation of the twister.

In the drawings, 1 represents the frame of a baling press supported in the usual man-

ner and extended rearwardly to form the bale chute 2, 3 the hopper, 4 the driving gears on the front portion of the frame, 5 the connecting rod with the gears for reciprocating the plunger head 6 within the frame, all being constructed and arranged in the ordinary manner.

The plunger 6 is formed with a middle longitudinal wall 7 inclosing a narrow chamber 8. Said wall is formed with transverse openings 9 and slots 11 extend therefrom through the face of the plunger. A shaft 12 journaled in the plunger is provided with a segmental gear 13 in engagement with pinion 10 and which carries an eccentric pin or roller 14 adapted to alternately engage with lever 15 fulcrumed on the frame and with a fixed stop 16 for turning said gear and shaft in respective opposite directions. A shaft 17 journaled in the plunger carries an intermediate gear 18 within chamber 8 and may be actuated from pinion 10 by means of the shaft and bevel gear connections 19 therewith. Twister gears 21 journaled within the chamber 8 engage with the intermediate gear 18 therein and are each formed with a radial slot 22 adapted to register with the corresponding slot 11 in the plunger. A plate 23 formed with racks 24 on its opposite edges and with a longitudinal track 25 is slidably mounted in guides 26 secured to the bottom 27 of the frame. A bar 28 pivotally secured at its front end to the plunger is slidably movable in the slotted bearings 29 which depend from the rack plate 23. Said bar is provided with a stop 31 near its rear end and with a laterally projecting lug 32 which is maintained in sliding engagement with the track under a yielding pressure by means of a spring 33.

A spring actuated bolt 35 slidably mounted in bearing 36 on the rack plate is adapted to automatically engage with a transverse hole 37 in bar 28 for locking the plate to move therewith. A transverse lug 38 secured on said bolt is formed with a longitudinally inclined face 39 and provided with a spring actuated pin 41. Said pin is adapted to automatically engage with a narrow inclined stop 42 which depends from the bottom 27 of the frame for preventing any rearward movement of the rack plate when the bolt 35 is disengaged from bar 28. When said bolt reengages bar 28 the pin 41 is

thereby moved laterally out of engagement with the inclined stop for permitting the rack plate to again move with said bar. A spring actuated guide pin 43 slidably mounted in a bracket 44 which depends from the bottom of the frame serves to engage with the inclined face 39 of lug 38 during the forward movement of the rack plate for moving the bolt 35 out of engagement with the hole 37 in bar 28. The continued forward movement of the plunger with bar 28 brings the stop 31 thereon into engagement with the adjacent bearing 29 and moves the rack plate a short distance farther for moving the bolt 35 clear of any contact with the side of said bar and also moves the pin 41 into engagement with the inclined stop 42 for locking the rack plate in longitudinal position.

A spring actuated switch 40 pivotally secured to the track 25 slidably engages with lug 32 on bar 28 for deflecting said bar in its forward movement with hole 37 therein out of registration with the bolt 35 thereby preventing the engagement of said bolt there-
with after it is released from guide pin 43. During the rearward movement of bar 28 lug 32 thereon rides on the track and under the switch with the hole 37 in registered position for the automatic engagement of the released bolt 35 therewith for reciprocating the rack plate.

A bell crank lever 50 pivotally mounted on bracket 44 engages with the guide pin 43 for moving it out of engagement with the inclined lug 38 and thereby permitting the bolt 35 to contact with the bar 28 and simultaneously move the pin 41 laterally out of engagement with the inclined stop 42. Said bolt being now released automatically engages with the hole 37 when in registration therewith during the rearward stroke of bar 28 for reciprocating the rack plate with said bar. A bell crank lever 45 pivotally secured on a bracket 46 which depends from the bottom of the frame is connected at one end with the free end of lever 50 by means of a rod 47. An idle notched wheel 48 journaled in bracket 46 carries an eccentric escape-
ment pin 49 for intercepting the free end of lever 45 and thereby actuating lever 50 through its connections therewith for moving the guide pin 43 to release the bolt 35. The periphery of said wheel projects through a slot in the bottom of the frame and within the chute 2. The contact of the moving bales in the chute therewith turns the wheel with the pin 49 into contact with lever 45 for releasing the bolt 35 at predetermined intervals for limiting the length of the bales to correspond to the size of the wheel. Vertical shafts 51 and 52 journaled on opposite sides of the frame are provided with pinions 53 in engagement with the respective racks 24 on the rack plate 23. Co-
operating curved arms 54 and 55 secured on

the respective shafts are movable thereby through the corresponding opening 9 in the middle wall 7 of the plunger 6 as shown in Fig. 7. An angular clamping finger 56 provided with a transverse pin 57 and pivotally secured on the extremity of each arm 54 may be maintained in either the closed or open position under a yielding pressure by means of the sliding engagement of a spring 58 with said pin. Said finger cooperates with the adjacent portion of said arm to which it is attached for either clamping or releasing the end portion of the tie wire 59. A blade 61 for cutting off the tie wire and also a curved member 62 actuated thereby for clamping said wire are pivotally mounted eccentric to each other on the extremity of each arm 55. Said blade may be maintained in either the closed or the open position under a yielding pressure by the sliding engagement of the transverse pin 63 therein with the spring 64. The pin 63 on the blade movably engages with the cam notch 66 formed in the edge of said member for actuating it into clamping position with the tie wire 59. The interior edge of member 62 is curved concentric to the pivotal center of the blade 61 for the movable engagement of pin 63 thereon for maintaining said member in the clamping position during the cutting movement of the cutter 61.

The tie wire 59 for each pair of arms is carried by a separate spool 68 supported on one side of the frame. Said wire may be directed over an idle pulley 69 mounted at a fixed point, thence under the clamp 62 and the cutter 61 by means of idle pulleys 71 and 72 on arm 55 thence around the rear end of the bale 73 and terminates in being securely clamped on arm 54 by means of finger 56 thereon. The rearward movement of the rack plate carries the arms 54 and 55 through the corresponding opening 9 in the wall of the plunger and with the wire in a crossed position within the radial slot 22 in the corresponding twister 21; the slotted bracket 74 secured on the rack plate simultaneously engages with and moves the lever 15 into engagement with the roller 14 on the segmental gear. The further movement of the rack plate causes the said lever to move the segmental gear and the twisters through their connections therewith for twisting the crossed wire therein securely together as shown in Fig. 7. With the completion of the movement of the twisters the finger 56 by contact of its top portion with a boss 75 on the plunger is thrown open and releases the tie wire as shown by dotted lines in Fig. 10 and the cutter 61 by simultaneous contact with the boss 76 on the plunger actuates the member 62 into clamping engagement with the tie wire and then severs said wire between said member and the bale 73 as shown in Fig. 8. Upon the completion of the rear-

ward stroke of the rack plate and the simultaneous severing of the tie wire by means of the cutter 61 the twisting of the wire is completed and the movement of the twister is stopped with the slot 22 therein in registration with the rear portion of the slot 11 for discharging the now twisted bale tie through said slot and the transverse wall of the plunger as shown in Fig. 16. The forward movement of the plunger with the rack plate actuates the arms 54 and 55 in an outward direction and finger 56 now being open catches the tie wire and is closed into clamping engagement with it by contacting with the top wall of opening 9 in its passage therethrough. The cutter by contact with the bottom edge of opening 9 in its passage therethrough is then opened together with the clamping member for releasing the end of the tie wire. During the further movement of the rack plate the tie wire is pulled through opening 9 by means of arm 54 and the lower edge of the segmental gear contacts successively with the steps of a two step lug 77 secured on the frame. The first step of said lug actuates said gear to impart a half turn to the twisters with the radial slot 22 therein in a forward direction as shown in Fig. 5 for receiving the wire laterally from opening 9. The second step of said lug serves to actuate the said gear to impart another half turn to the twisters with the radial slot 22 therein in registration with the rear portion of slot 11 in the plunger wall as shown in Fig. 16 for discharging the wire therethrough that it may encircle the succeeding bale as shown in Fig. 1. At the completion of the forward stroke of the rack plate it is disengaged from the plunger by means of the locking bolt 35 and maintained immovable with the arms 54 and 55 in the open position until reengaged by the mechanism actuated by the wheel 48 after a full turn thereof by contact with the moving bales in chute 2. The contact of stop 16 with the roller 14 at the completion of the forward movement of the rack plate actuates the segmental gear with its connections to turn the twisters in the position shown in Fig. 5 to again receive the tie wire.

In operation, the reciprocating plunger presses the material rearwardly within the chute to form the bale. The forming bale draws the tie wire slowly from the spool and around its rear end. The measuring wheel at predetermined intervals actuates its connections to effect the engagement of the rack plate with the plunger thereby moving the arms with the tie wires in proper position within the twisters. The further movement of the rack plate with the plunger actuates the segmental gear by contact with the fulcrumed lever to turn the twisters with the wires therein for completing the tying of the bale. The finger clamps are then re-

leased from the end of the tie and reengaged with the tie wires leading from the spools and the completed ties are severed from the tie wires leading from the spools. The completed ties are then discharged from the 70 twister and through the slots in the plunger and the twisters are actuated by the segmental gear through the engagement of the two step lug therewith for imparting successive half turns thereto for permitting the 75 tie wires to escape therethrough and in the proper position to be drawn from the spools and automatically around the succeeding bale. At the completion of each forward movement of the rack plate it is automatically disengaged from the plunger by means of the engagement of the locking bolt with the spring actuated stop.

Having fully described my improvement, what I claim as my invention and desire to 85 secure by Letters Patent of the United States is:—

1. In a baling press the combination of a frame, a plunger head mounted to reciprocate therein and formed with a transverse 90 slot through its face, a wire twister journaled in said head in registration with the slot therein, automatic mechanism mounted on opposite sides of the frame for inserting a crossed wire within the twister, and automatic mechanism for actuating the twister intermittently during a stroke of the head.

2. The combination of a rectangular tubular frame, a plunger head mounted to reciprocate therein, and formed with an open 100 slot through its face, a twister journaled in the plunger in registration with the slot therein, wire carrying arms pivotally secured on respective opposite sides of the frame, means for intermittently actuating 105 said arms to insert a crossed wire within the twister, and automatic means for actuating the twister at successive intervals in the stroke of the plunger for twisting and for releasing the wire through said slot in the 110 head.

3. The combination of a frame, a plunger head mounted to reciprocate therein and provided with a wire twister, carrying arms pivotally mounted on respective opposite 115 sides of the frame for inserting a crossed wire within the twister, connections with the head for actuating the arms at predetermined intervals in its movement, and for actuating the twister.

4. The combination of a frame, a plunger head mounted to reciprocate therein and provided with a wire twister, driven connections with said head, mechanism for inserting a crossed wire within the twister at pre-determined intervals in the movement of the head, and means actuated by the movement of the head for actuating the twister intermittently.

5. The combination of a frame, a plunger 130

- head mounted to reciprocate therein, a twister carried by the head, arms pivotally secured on the frame for feeding wire to the twister at predetermined intervals in the movement of the head, and connections actuated by the movement of the plunger for imparting intermittent motion to the twister.
6. The combination of a frame, a reciprocating member therein, a twister carried by said member and formed with an open radial slot, and automatic mechanism actuated by the movement of said member for adjusting the twister with the slot therein in opposite directions respectively at predetermined intervals.
7. The combination of a frame, a plunger therein, formed with an open slot through its face, a twister journaled in the plunger and formed with an open radial slot adapted to register with the former slot at predetermined intervals, and means secured on the frame and actuated by the movement of the plunger for rotatively adjusting the twister.
8. The combination of a frame, a lever fulcrumed thereon, a plunger, a segmental gear thereon, a twister in the plunger, connections from the gear therewith, and driven connections for reciprocating the plunger with the gear into engagement with the lever for actuating the twister.
9. The combination of a frame, a reciprocating plunger therein provided with a twister, arms secured on the frame for inserting wire within the twister, and automatic mechanism for actuating the arms during predetermined strokes of the plunger.
10. The combination of a frame, a reciprocating plunger therein provided with a wire twister, automatic mechanism movably secured on the frame for inserting wires into the twister from respective opposite sides of the plunger, and automatic means for detachably engaging said mechanism with the plunger.
11. The combination of a frame, a reciprocating plunger therein, a wire twister journaled in the plunger, automatic wire feeding mechanism therefor secured on the frame, and detachable connections from the plunger with said mechanism.
12. The combination of a frame, a reciprocating plunger therein, a twister carried by the plunger, and automatic mechanism secured on the frame for actuating the twister and for detachably engaging therewith at predetermined intervals during the movement of the plunger.
13. The combination of a frame, a plunger head movable therein, a twister journaled in the said head and formed with a radial slot, arms mounted on the frame and provided with clamping devices for the tie wire, and rack and pinion mechanism actu-

ated by the movement of the head for moving the arms with the tie wire into the slot of the twister.

14. A baling press comprising a frame, a plunger, mechanism carried by the plunger for tying the bale, a tie wire, and automatic mechanism mounted on the frame and actuated by the movement of the plunger for engaging the tie wire with said tying mechanism.

15. A baling press comprising a frame, a reciprocating plunger therein and provided with a wire twister, arms secured on the frame for feeding wire to the twister, and connections with the head for actuating the arms and the twister alternately at predetermined intervals.

16. A baling press comprising a plunger provided with tying mechanism, a plate, arms actuated thereby for engaging the tie wire with said mechanism, means for detachably engaging the plate to move with the plunger, and an automatic measuring device for actuating said means for maintaining uniformity in the length of the bales.

17. In a baling press, the combination of a frame, a reciprocating plunger therein formed with an open slot a twister journaled in the head and formed with a radial slot, and connections with the head for rotating the twister at intervals with the slot therein alternately in registration with respective opposite portions of said open slot.

18. A baling press comprising a frame, a plunger head mounted to reciprocate therein and formed with a transverse opening and with a transverse slot extending therefrom through its face, a twister journaled in the head in the line of said slot and formed with a radial slot adapted to register alternately with opposite ends of the slot in the head, mechanism constructed and arranged for feeding wire from opposite sides through the opening in the head and within the slot in the twister, means for securing the wire, and connections with the head for actuating the twister to twist the wire and discharge it through the portion of the slot opposite the opening in the head.

19. A baling press provided with a plunger, having a transverse opening, a wire twister carried thereby, arms movable in opposite directions respectively through said opening, an automatic clamping device on one arm, an automatic wire cutter and co-operating clamping device on the other arm, and connections for detachably engaging the arms to co-operate with the twister for tying a bale tie wire.

20. A baling press comprising a plunger, a wire twister carried thereby, automatic means for detachably engaging a tie wire therewith, automatic means for actuating

- the twister, means for successively clamping and releasing the wire, an automatic knife for cutting the wire, and a wire clamp for coöperating with the knife.
- 5 21. A baling press comprising a movable arm, a wire cutter pivotally mounted thereon, a clamp pivotally mounted eccentric to the cutter and movable therewith, and separate means for opening and closing the cutter with the clamp.
22. A baling press comprising a frame, a reciprocating plunger therein, a wire twister carried by the plunger, means for engaging and actuating the twister during 15 certain strokes of the plunger, wire carrying arms pivotally secured on the frame and provided with means for automatically engaging with a tie wire, and rack and pinion mechanism for actuating the arms 20 to coöperate with the movement of the plunger.
23. A baling press comprising a frame, a plunger therein, a rack plate, and automatic mechanism for engaging the plate to move 25 with the plunger at intervals in its strokes.
24. A baling press comprising a frame, a plunger therein, a twister carried by the plunger, movable arms pivotally secured on the frame and provided with automatic 30 wire clamps, and automatic connections for actuating the arms by the movement of the plunger to coöperate with the twister.
25. A baling press comprising a wire twister journaled in a slotted bearing and 35 formed with a radial slot adapted to regis-
- ter alternately with opposite portions of the slot in the bearing.
26. In a baling press, the combination of a plunger formed with a divided bearing, a wire twister journaled in said bearing and 40 formed with a radial slot, automatic means for inserting a crossed wire within the slot in the twister and connections with the plunger for rotating the twister intermittently with the slot therein into registration 45 alternately with opposite sides of the divided bearing.
27. In a baling press, a bearing formed with a diametrical slot therethrough, a twister journaled therein and formed with 50 a radial slot, and driven connections for rotatively adjusting the twister with the slot therein into registration successively with opposite portions of the slot through the bearing.
28. In a baling press, the combination of a bearing formed with a diametrical slot, a twister journaled therein and formed with 55 a radial slot, means for inserting a wire through one end of the bearing slot and within the slot in the twister, and means for adjusting the twister with the slot therein into registration with the opposite end of the bearing slot for discharging the wire therethrough.
